BLASTING CAP

Frank Rosenthal, San Andreas, Calif.

Application June 18, 1934, Serial No. 731,045

8 Claims. (CL 102—9)

This invention relates to blasting caps or fuse caps containing explosive compounds as used for detonating dynamite and other high explosives, and the objects of the invention are to provide improvements in such caps which will reduce the percentage of misfires to which such caps are now subject.

In the drawing accompanying this application the figures show:

10 Fig. 1, a longitudinal section of a regular exploder cap with fuse inserted and crimped in place.

Fig. 2, a longitudinal section of a fuse and cap combination similar to that of Fig. 1 but showing 15 the explosive formed with a grooved surface.

Fig. 3 is a cross section of Fig. 2 as seen from the line 3—3 of Fig. 2.

Fig. 4, a longitudinal section of a cap and its 20 charge of fulminate or the like formed with a surface grooved in across directions.

Fig. 5, a cross section of Fig. 4 taken along the line 5—5 thereof.

Fig. 6 is a view of a blasting cap similar to that of Fig. 4 but showing a still further modification 25 of the surface formation of the detonating compound.

Fig. 7 is a cross section of Fig. 6 taken along the line 7—7 thereof.

Fig. 8 is a view similar to that of Fig. 4 but 30 shows the compound formed on its surface with but one central protuberance.

Fig. 9 is a view of a blasting cap similar to that of Figs. 4 or 2 but with the side wall of the shell swelled outwardly at a point adjacent the 35 detonating mixture.

Before describing the invention in detail, attention is called to the construction in Fig. 1 which shows (somewhat enlarged) an ordinary detonating cap in which 1 is a thin copper or other metal shell closed at one end 2 and containing a relatively small quantity of detonating compound 3, generally a mercury fulminate mixture compressed tightly into the shell by means 40 of a small press plunger rod, not shown in the drawing, while into this shell projects a fuse 4 of conventional construction carrying an internal powder train 5. The fuse is cut off straight, or, rather, at right angles at its inner end so as to 45 seat tightly against the explosive compound, and the shell is crimped to the fuse as indicated at 6 or otherwise to hold the combination together, and the juncture of the shell and fuse may be 50 coated with varnish, pitch, rubber or other agencies, to seal the joint when desired to prevent any

possibility of water getting in when the fuse is used in damp places.

In such fuse and cap combinations it is found difficult to insure the end of the fuse or powder train 5 contacting the fulminate or other explosive compound 3 in a manner to insure firing, and if a slight space exists between these elements of the combination, gases may accumulate as the fuse burns down into the shell and build up a pressure at this point so that the advancing flame is forced back, and/or the fuse itself may be forced back slightly or the pressure of spent gases puts the fire out. Just what is the precise cause of the failures frequently met with may not be known but it is obviously due to one or more of the reasons above given, and it is to avoid such firing failures and the loss of effectiveness of a blast where several holes must be shot in succession, together with the great danger attendant upon having unexploded charges to contend with, that my improvements have been worked out.

The principal feature of my invention is the provision of a grooved, slotted, corrugated, or otherwise roughened, surface on the detonating compound to afford lateral passage for the gases should they accumulate, either for escape of the gas along the sides of the fuse if not crimped too tightly, or for compression within the groove or grooves while still permitting the fuse train 10 to remain in contact with at least one or more raised points of the compound.

In Figs. 2 and 3 the grooving of the surface of the detonating compound takes the form of simple parallel grooves 1.

In Figs. 4 and 5 the grooves 8 are arranged as two pairs in crossing relation.

In Figs. 6 and 7 the grooves 9 are arranged radially while preserving a small central nucleus 10 which would impinge the powder train.

In Fig. 8 the central nucleus of Fig. 6 has been exaggerated into a rounding central lump 12 adapted to be almost forced into the powder train when the fuse is pushed into the cap even though the train should be retracted somewhat 45 from loss of powder, and still preserve a circular passageway for escape of or compression of gases which may form.

In Fig. 9 a still further modification shows the surface of the detonating compound corrugated or grooved, as in Fig. 2, to present little ridges or elevations to the flame of the fuse, and this view also shows a localized outward bulge 11 adjacent the surface of the compound 3 which provides a pocket in which the gases may com-

press while still leaving the fuse in contact with one or more ridges of the compound. The bulged portion 11 may extend as a ring around the shell, or go but part way around, or may be a series 5 of bulges, and there may be any number of large or small bulges around the shell for the purpose set out.

In forming the slots, corrugations, ridges, or elevations, on the surface of the compound the 10 punch used to force the material into the cap shell is simply made in counterform to the design of surface modeling desired, and thus it entails no more labor to have the surface formed in any of the designs shown than to use a plain nosed punch.

It is, of course, apparent that while I have shown the grooves, ridges, etc., arranged in a regular pattern, this is not necessarily so as the undulations or protuberances may be of an 20 irregular pattern if desired. It is, however, desirable that the small indentations and protuberances be more or less rounded at their edges to avoid the danger of small particles of the compound becoming chipped off or dislodged.

Having thus described my improved construction 25 in blasting caps, what I claim is:

1. A fuse cap comprising a shell containing a 30 quantity of a detonating compound compacted into one end and presenting a surface adapted to contact the end of the powder train of a fuse inserted into the shell, and said surface of the compound formed with a gas escape channel leading to the wall of the shell.

2. A fuse cap comprising a shell containing a 35 quantity of a detonating compound compacted into one end, and the surface of the compound formed with grooves and ridges, said grooves extending to the wall of the shell.

3. A fuse cap comprising a shell containing a

quantity of a detonating compound compacted into one end, and the surface of the compound formed with grooves and ridges in crossing arrangement.

4. A fuse cap comprising a shell containing a 5 quantity of a detonating compound compacted into one end, and the surface of the compound formed with a central protuberance adapted to impinge the powder train of a fuse inserted in the shell.

5. A fuse cap comprising a shell containing a 10 quantity of a detonating compound compacted into one end and against which compound the end of a fuse inserted in the shell is adapted to contact, and an outwardly bulged pocket in the 15 shell wall providing a receiving space for accumulated gas of fuse combustion.

6. In a construction as specified in claim 5, 20 said outwardly bulged pocket in the shell wall extending substantially around the same.

7. A fuse cap comprising a shell containing a 25 quantity of a detonating compound compacted into one end and against which compound the end of the powder train of a fuse inserted in the shell is adapted to contact, a pocket formed in the surface of the compound adjacent the end of the fuse adapted for receiving a small amount of gas under pressure, and a pocket for similar purpose formed in the shell.

8. A fuse cap comprising a shell containing a 30 quantity of a detonating compound compacted into one end and against which compound the end of the powder train of a fuse inserted in the shell is adapted to contact, a pocket formed in the 35 surface of the compound adjacent the end of the fuse adapted for receiving a small amount of gas under pressure, and an annular pocket for similar purpose formed in the shell.
